(57) **CLAIM**

The ornamental design for a automobile and toy replica thereof, as shown and described.

DESCRIPTION

FIG. 1 is a left front perspective view of a first embodiment of an automobile and toy replica thereof of our new design;

FIG. 2 is a left rear perspective view thereof;

FIG. 3 is a front elevational view thereof;

FIG. 4 is a rear elevational view thereof;

FIG. 5 is a left side elevational view thereof, the right side elevational view being a mirror image of FIG. 5, with the exception of the windshield wiper assemblies which are not symmetric;

FIG. 6 is a top plan view thereof;

FIG. 7 is a left front perspective view of a second embodiment of an automobile and toy replica thereof of our new design;

FIG. 8 is a left rear perspective view of FIG. 7;

FIG. 9 is a front elevational view of FIG. 7;

FIG. 10 is a rear elevational view of FIG. 7;

FIG. 11 is a left side elevational view of FIG. 7, the right side elevational view being a mirror image of FIG. 11, with the exception of the windshield wiper assemblies which are not symmetric; and,

FIG. 12 is a top plan view of FIG. 7.
